(57) **CLAIM**

The ornamental design for a sash to frame connecting member profile as shown and described.

DESCRIPTION

FIG. 1 is a side-elevation view of the sash to frame connecting member profile showing the design;

FIG. 2 is a first isometric view thereof from above;

FIG. 3 is a second isometric view thereof from above;

FIG. 4 is a first isometric view thereof from below; and,

FIG. 5 is a second isometric view thereof from below.

The break lines are used for the purpose of illustrating a break in the length of the article and do not form part of the design.

1 Claim, 5 Drawing Sheets
